Attorneys

UNITED STATES PATENT OFFICE.

MILTON L. HELLER, OF BROOKLYN, NEW YORK.

WAISTBAND.

Application filed March 18, 1922. Serial No. 544,914.

To all whom it may concern:

Be it known that I, MILTON L. HELLER, a citizen of the United States, residing at Brooklyn, in the county of Kings and State 5 of New York, have invented certain new and useful Improvements in Waistbands; and I do hereby declare the following to be a full, clear, and exact description of the invention, such as will enable others skilled in 10 the art to which it appertains to make and use the same.

This invention relates to new and useful improvements in waist bands, and more particularly to waist bands upon children's 15 trousers, the main object of the present invention being the provision of an improved waist band having stiffening means embodied therein adapted not only to enable the band to stand up but to reenforce the 20 band and button holes; an additional object is to provide reenforcing stitching in conjunction with said stiffening means to lend additional strength to the buttonhole strip of the band, and at the same time 25 strengthen the waist band throughout its entire length with the use of a minimum amount of material.

A further object of the present invention is the provision of a waistband in which the 30 customary scalloping or other means heretofore employed for holding the buttonhole strip of the waistband up in position are eliminated by virtue of the employment of 35 stiffening means within the waist band through its entire length.

A still further object of the invention is to equalize the strength of material at both 40 ends of the buttonhole so that the one end of the buttonhole is as strong as the other.

With the above and other objects in view, the invention consists in the novel features 45 of construction, combination and arrangement of parts hereinafter more fully set forth, pointed out in the claims and shown in the accompanying drawings, in which:

Figure 1 is a perspective view of the upper portion of a pair of trousers having my improved waist band applied thereto;

Figure 2 is a detail elevation of a portion 50 of the band, and

Figure 3 is a transverse sectional view.

Figure 4 is a similar sectional view taken through a buttonhole.

Referring now more particularly to the 55 drawings, the numeral 1 indicates the trousers having my improved waist band 2 ap-

plied thereto. The waist band is preferably formed of three pieces of material consisting of a buttonhole strip 3 and an attaching strip 4, the attaching strip being 60 positioned between the buttonhole strip 3 and the material of the trousers 1, as clearly shown in Fig. 3. The third part of the band is a stiffening strip 5 included within the button hole strip 3 and forming the essential 65 part of the invention.

In the construction of my improved waist band, the band is made up of any suitable material. The material of the button hole strip is first arranged upon one side of the stiffening strip 5, as at 6, and then brought over upper edge of the stiffening strip folded upon itself as at 7, to form a hem along the upper longitudinal edge of the buttonhole strip. This hem is then stitched down onto 75 the stiffening strip, the stitching passing through and embracing the portion 6 of the buttonhole strip. The facing material is then brought downwardly over the lining and folded upon itself to form a pleat as at 80 10. This pleat is preferably arranged at the lower ends of the buttonholes 9 and in stitching this pleat 10 into position, a straight line of stitching 11 is used, said stitching extending through and embracing 85 the inner stiffening strip 5, one of the longitudinal edges of the material of the buttonhole strip and the lower edge of the attaching strip 4, thus the one straight line of stitching 11 not only holds the pleat 10 in 90 position, but is utilized to connect the stiffening 5 with the buttonhole strip and attaching strip 4. By arranging this pleat 10 along the waist band 2 in spaced relation with the hem 7, the button holes 9 are additionally reenforced at each end thereof, thus preventing any tearing out or ripping of 95 the buttonholes. It is to be noted that the stiffening strip is enclosed within the buttonhole strip and secured by both lines of 100 stitching at the top and bottom of the buttonholes, and the holes are made so the stitching therearound unites the front and back of the buttonhole strip and stiffening strip. Also the hem combined with stiffening strip and the front and back of the buttonhole strip provides five plies of material 105 at the top of the buttonholes. Similarly the pleat combined with the stiffening strip and the front and back of the buttonhole strip provides five plies of material at the bottom of the buttonholes. By this con-

110

struction the top and bottom of the button holes are of equal strength and are amply reenforced so as to be very strong and not likely to be torn out. Furthermore, use of the stiffening strip not only holds the waistband upright, avoiding the necessity of scallops and the resulting inconvenience of buttoning, but also gives "body" or a more shapely appearance to the trousers embodying the invention.

After the buttonhole strip has been secured by the line of stitching 11, the additional amount of material is extended down and around the lower edge of the stiffening strip 5 and the lower longitudinal edge of the buttonhole strip is folded onto the back of the stiffening strip and the buttonhole strip and stiffening strip are then secured by the line of stitching 12 to the body of the garment 1. The attaching strip is sewn to the trousers 1 at a point adjacent its upper edge by means of the line of stitching 13.

Attention is called to the fact that by connecting the stiffening strip 5 to the buttonhole strip, additional strength is provided for whereby to retain the buttonhole strip in an upright position and prevent the same from flapping over toward the inside of the body of the trousers.

By constructing a waist band as set forth above, reduces labor expense in the construction of the band enough or more than enough to counterbalance the additional expense of material and at the same time adds to the strength of the band throughout its

entire length, and particularly at the ends of the buttonholes where this strength is most needed.

Having thus described my invention I claim:

1. A waistband comprising a buttonhole strip having buttonholes at intervals throughout its length, said strip being folded on itself with a hem formed at the top and bottom of said buttonholes, and a stiffening strip interposed between the layers of buttonhole strip, thereby forming an equal number of layers of material adjacent the top and bottom of said buttonholes.

2. A waistband in combination with a pair of trousers comprising a buttonhole strip having buttonholes at intervals throughout its length, said strip being attached to said trousers a distance below the upper edge thereof, said strip being folded upon itself adjacent the lower ends of the buttonholes and again at a point adjacent the upper edge of said buttonholes, and extending down to a point adjacent the point of attachment to said trousers, a stiffening strip between the spaced folds of said buttonhole strip, and an attaching strip fastened at its upper end to the edge of said trousers, and at its lower end to said buttonhole strip adjacent its first mentioned fold.

In testimony whereof I affix my signature.

MILTON L. HELLER.
